FILING TRAY OR THE LIKE

Lloyd M. Toms, Crozet, Va., assignor to Acme Visible Records, Inc., Crozet, Va., a corporation of Virginia

Filed Nov. 4, 1963, Ser. No. 77,319

Term of patent 14 years

(Cl. D74—9)

FIG. 1 is a front perspective view of a filing tray showing my new design.

FIG. 2 is a side elevational view thereof which discloses an L-shaped leg support mounted on the rear surface of the tray for supporting the tray in an inclined position. The L-shaped support is of conventional design.

The design for the filing tray is characterized by the beveled front and lower end portion, grooved indicia containing channel along one side edge of the tray and the combination of the flat and grooved indicia carrying members between the sides of the tray as shown.

I claim:

The ornamental design for a filing tray or the like, substantially as shown and described.
